INVENTOR:

Edward Heid,
BY
E. T. Silvius.
ATTORNEY.

UNITED STATES PATENT OFFICE.

EDWARD HEID, OF INDIANAPOLIS, INDIANA.

AUTOMATIC SASH-LOCK.

No. 922,894.

Specification of Letters Patent.

Patented May 25, 1909.

Application filed February 25, 1909. Serial No. 479,996.

To all whom it may concern:

Be it known that I, EDWARD HEID, a citizen of the United States, residing at Indianapolis, in the county of Marion and State of Indiana, have invented certain new and useful Improvements in Automatic Sash-Locks; and I do declare the following to be a full, clear, and exact description of the invention, reference being had to the accompanying 10 drawings, and to the letters of reference marked thereon, which form a part of this specification.

This invention relates to locks or fasteners for vertically sliding window sashes that are 15 used in pairs, comprising each a lower sash and an upper sash, either balanced or without balance weights, the invention having reference particularly to devices whereby the sashes may be prevented from being opened, 20 or whereby when either sash is opened purposely to a limited extent it may be locked or latched to prevent further movement of the sash in its frame by persons outside of the building.

25 An object of the invention is to provide reliable sash locks especially adapted to permit the upper sash to be lowered for ventilating purposes and securely locked for limiting the amount of opening above the sash, 30 a further object being to provide a sash lock that will automatically lock both sashes in closed position when either or both sashes have been closed after having been opened to a limited extent for ventilating purposes, it 35 being an object of the invention to provide locks whereby the ventilating openings may be limited in extent so that prowlers or sneak thieves can not enter the restricted openings.

A still further object is to provide an automatic sash lock that will be adapted to be applied readily to window sashes that are already in use, and be strong and durable.

The invention consists in a ratchet-toothed bar adapted to be attached to an upper sash, 45 and a novel spring pressed catch adapted to be attached to the top of the lower sash to coöperate with the latch bar, the invention consisting further in the parts and combinations and arrangements of parts, as hereininafter particularly described and afterward defined in the accompanying claim.

Referring to the drawings Figure 1 is a fragmentary elevation of the inner side of a wall and a window therein provided with the 55 improved sash locks; Fig. 2, a vertical sectional view on the line A A in Fig. 1; Fig. 3,

a fragmentary elevation reproducing a portion of Fig. 1 on an enlarged scale; Fig. 4, a fragmentary sectional view taken near the line B B in Fig. 3; Fig. 5, a fragmentary vertical section approximately at the plane of the line C C in Fig. 4; Fig. 6, a perspective view of the improved latch; Fig. 7, a perspective view of the supporting base of the latch; and Fig. 8, a front or plan view of the 65 latch bar.

Similar reference characters in the drawings indicate like parts or features of construction referred to herein.

In the drawings, *a* indicates the sill, *b* and *c* the upright side parts and *d* the top part of a window frame, *e* indicating the upper sash, and *f* the lower sash of the window mounted in the usual manner, so as to slide vertically.

The invention comprises two latch bars *g* 75 and *g'* of identical construction which are secured to the inner side of the lower portion of the upper sash *e* and extend substantially from the lower end of the sash upward along the side parts of the sash to any desired extent, each latch bar being preferably of such length that it will serve as an indicator as to the extent that the upper sash should be lowered or the lower sash raised safely in order to prevent admission of a person 80 through the opening. Each latch bar has a plurality of inclined angular faces *h* and abrupt shoulders *i* constituting ratchet-teeth, and the ends of the bar have apertures *j* and *j'* therein to receive screws *k*, 85 whereby the bars are secured rigidly to the sash, the bars extending a short distance behind the upper portion of the lower sash. A pair of latches *l* and *l'* constituting ratchet dogs are mounted on the top of the lower 95 sash and are spring pressed into engagement with the ratchet-teeth of the latch bars so that they will engage the shoulders *i* and normally prevent the upper sash from being lowered or raising of the lower sash, each 100 latch having an operating lever *m* formed thereon. The body portion *n* of the latch is relatively thick and strong and has an abutment *o* formed at the under side thereof so as to be practically at the lower end of the 105 latch, a portion of the body of the latch being formed as a relatively thin wing *p* in which is a pivot hole *q*. Each latch has a supporting base plate *r* on which two wings *s* and *s'* are formed that have pivot holes *t* and *t'* 110 therein respectively, the plate having apertures *u* and *u'* therein to receive securing

screws, the latch being connected to the ears by a pivot pin v so that the latch will rock toward or from the latch bar, the plate being secured on the top of the sash by screws w and w' , so as to be opposite either latch bar. A coil spring x encircles the pivot-pin between the ear s and the wing p of the latch body and has an arm y that engages the top of the base plate r , the spring having another arm y' that extends into a groove z in the under side of the lever n adjacent to the wing p , the end of the arm y' having an angular hook-like projection y'' that enters a socket z' in the under side of the lever at the end of the groove therein so that the arm y' is prevented from dislodgment in operation.

By reference to Fig. 4 it will be seen that the abutment o is normally spring pressed against the top of the base plate r when the latch dog l is engaging a shoulder i so that the thrust is sustained without straining the pivot of the latch, and this also prevents the latch from engaging and marring the surface of the upper sash when the sash is moved so as to carry the latch bar down out of reach of the latch.

In practical use when both sashes are closed the latches l and l' will engage the ratchet-teeth of the lock bars l and l' at the lower ends of the latch bars and normally prevent movement of either one of the sashes. In order to either lower the upper sash or raise the lower sash the levers m of the latches must be depressed so as to disconnect the latches or dogs from the ratchet-teeth, and then either sash may be moved, and inasmuch as the latch bars may be seen above the lower sash it is clear that either sash may be moved until the dogs engage the uppermost shoulders i on the latch bars which will indicate that the sash has been

moved within the predetermined limit. If occasion requires it, however, the sashes may be moved to a greater extent, as will be apparent, and when the open sash is being closed it will be seen that the latches will be spring pressed against the inclined faces h of the ratchet-teeth until the sash is stopped, either in closed position or partly closed, and will automatically engage the shoulders i and prevent either sash from again being opened except by operating the latch levers. It will be clear, therefore, when a room has been ventilated and the open sash has been closed it will become automatically locked so that it can not be opened from the outside, and therefore a window can not be carelessly left unlocked after having been closed or when opened to the desired extent for ventilating purposes.

Having thus described the invention, what is claimed as new, is—

A sash lock comprising a base plate having two ears thereon, a latch dog having an operating lever and also an abutment thereon and arranged between the two ears, the body part of the dog having a relatively thin wing, a pivot-pin connecting the wing to the two ears, a spring on the pivot-pin between an ear and the wing and having an arm engaging the base plate and also an arm engaging the lever, said spring normally holding the abutment in contact with the base plate, and a ratchet-toothed latch-bar to be engaged by the latch dog.

In testimony whereof, I affix my signature in presence of two witnesses.

EDWARD HEID.
